CLAIM

We claim the ornamental design for a gait rehabilitation robot, as shown and described.

DESCRIPTION

FIG. 1 is a top perspective view of a gait rehabilitation robot, showing our new design.

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a bottom perspective view thereof.

The dash-dash broken lines shown are included for the purpose of illustrating portions of the gait rehabilitation robot that form no part of the claimed design. The dot-dash broken lines depict boundaries of the claim and form no part thereof.
